RAIL BENDER

Lester O. Becker, St. Louis, Mo., assignor to Joseph Pavelka, St. Louis, Mo.

Application September 9, 1937, Serial No. 162,971

2 Claims. (Cl. 153—38)

The invention relates to rail benders and consists in novel means visibly indicating the extent to which such a device has been operated.

In using rail benders it is frequently desirable that successive rails be bent to the same extent so that the degree of curvature of the rails may be substantially uniform. The usual method of determining when a second rail has been bent to the same degree as the previously bent rail, is to lay the rails on top of each other or to bend the rail in the bending device until the rail meets markers which have been set up for that purpose.

The principal object of the present invention is to provide visible indicating means in the bending device itself, whereby the extent to which the rail has been bent may readily be determined by the operator without comparing the end portions of the rail with another rail or marker.

Again it may be desired to maintain a known variation in the degree of bending of successive rails and it is another object of the present invention to facilitate such relative bending of different rails.

These and other detailed objects of the invention, as will appear from the following description, are attained by the structure illustrated in the accompanying drawing, in which:

Figure 1 is, in part, a top view and in part a section through a rail bender with a rail in position therein, the bending of the rail being indicated in broken lines;

Figure 2 is a front elevation of the same structure;

Figures 3 and 4 are cross sections taken on the section lines 2—2 and 3—3, respectively, of Figure 1;

Figure 5 is a detailed section corresponding to the right hand portion of Figure 3 and illustrating a modified form of the invention, and

Figure 6 is an end view of the structure shown in Figure 5.

The body 1 of the bender is substantially triangular in contour with jaws 2 at its ends arranged to receive the head of a rail R. A screw 3 is journalled in a socket 4 in a cylindrical housing formed at the middle portion of the body and a nut 5, threaded on screw 3, is positioned in a recess 6 in the body, and has an antifriction bearing unit 7 seated against one side of the recess. The latter mentioned parts form a jack-like structure for applying pressure through the screw head 8 to the inner face of the rail head intermediate jaws 2, whereby, as the nut is rotated,

it will force the screw head and rail to the position indicated by broken lines in Figure 1.

A pin 9 on the rear portion of screw 3 slides in a slot 10 provided in the screw socket 4 and, when the head of the screw is not engaged by a rail, pin 9 holds the screw against rotation and limits its outward movement. As the pin moves along slot 10 it comes abreast of successive markings 11 on the exterior of the housing, thereby indicating the extent to which the screw head 10 has moved outwardly from the frame and, accordingly, the degree to which the rail has been bent, hence when an operator has bent one rail until the screw pointer 9 reaches the "3" mark on the scale, and the rail is then deemed bent to the desired extent, it is a simple matter for the operator to terminate the bending of succeeding rails with the pointer 9 at the same point on the scale. This will result in such rails having approximately the same degree of curvature and this will be true irrespective of the fact that the rails may possess sufficient elasticity to spring back somewhat after they have been bent.

It is desirable, although not essential, that the elongated slot 10 be closed, except at the point pin 9 projects, to minimize the amount of dirt entering the screw-receiving socket 4. For this purpose there is provided a closure plate 12, slideable about the inner wall of socket 4 and having a slot 13 disposed at an angle to slot 10. As screw 3 and pin 9 travel along socket 4, plate 12 will be rotated by the pin so as to accommodate the latter's travel and at the same time maintain the remainder of the slot closed.

In the modification illustrated in Figures 5 and 6 the screw socket 15 has no slot in its side corresponding to slot 10, but there is an opening 16 in the rear end of the socket and a flat strip 17 bent into a helical ribbon, projects through opening 16 and into an elongated recess 18, provided in screw 19. A plate 20 on the end of screw 19 has a restricted rectangular opening for strip 17 and as screw 19 is moved outwardly and inwardly of the socket it will rotate the helical ribbon. A pointer 21 on the end of strip 17 is thereby rotated about the axis of the strip and screw to travel over a graduated scale 22 provided on a plate 23, applied to the outer end of socket member 15. It will be noted that screw 19 has no rotary movement (due to the engagement of its head with the rail head similarly to the head 8 of screw 3) but, like screw 3, moves in and out when a nut corresponding to nut 5 is rotated.

Obviously, this form of the invention func-

tions similarly to the arrangement previously described and the operator may duplicate successive operations of the bender as desired.

With either form of the invention the relation between successive movements of the screw may be determined by comparing the readings of the indicator. If desired, the scale markings may indicate inches or quarter inches of movement of the screw head, but this is not material. The markings may be purely arbitrary and not expressive of units of measurement.

The invention is shown applied to a preferred form of rail bender, but it will be understood that the general concept is applicable to other types of benders and also that the details of the indicating device may be changed substantially from that shown without departing from the spirit of the invention. The exclusive use of such modifications as come within the scope of the claims is contemplated.

I claim:

1. In a device of the class described, a frame including a hollow socket member, a pressure applying bar movable lengthwise in said socket member, there being a slot in the side of said

member, a cover plate for said slot and having a slot disposed at an angle to said member slot and intersecting the same, and a pointer on said bar projecting through both of said slots and movable along said first mentioned slot to indicate the extent of movement of said bar and to slide said plate over said first-mentioned slot to keep all of the latter covered except where said pointer projects.

2. In a device of the class described, a frame including a hollow socket member of curved cross section, a pressure-applying bar movable lengthwise in said socket member, there being a slot in the side of said member, a cover plate of curved cross section for said slot and received within the socket member and having a slot disposed at an angle to said member slot and intersecting the same, and a pointer on said bar projecting through both of said slots and movable along said first-mentioned slot to indicate the extended movement of said bar and to slide said plate over said first-mentioned slot to keep all of the latter covered except where said pointer projects.
